UNITED STATES PATENT OFFICE

154,874

DESIGN FOR A DOMESTIC RANGE OR SIMILAR ARTICLE

Frederick M. Pence, Los Angeles, Calif., assignor
to Thermador Electrical Manufacturing Com-
pany, Los Angeles, Calif., a corporation of
California

Application August 18, 1947, Serial No. 140,930

Term of patent 14 years

(CL. D81—25)

To all whom it may concern:

Be it known that I, Frederick M. Pence, a citizen of the United States, residing in Los Angeles, in the county of Los Angeles, State of California, have invented a new, original, and ornamental Design for a Domestic Range or Similar Article, of which the following is a specification, reference being had to the accompanying drawing, forming a part thereof.

Figure 1 is a perspective view of a domestic range or similar article embodying my new and ornamental design.

Figure 2 is a sectional view taken on line 2—2 of Figure 1.

The essential features of my design reside in the portions shown in full lines.

I claim:

The ornamental design for a domestic range or similar article, as shown and described.

FREDERICK M. PENCE.
